(57) **ABSTRACT**

A new and distinct cultivar of *Dianthus* plant named 'KonD1335K1', characterized by its uniformly mounding and upright to broadly spreading plant habit; dense and bushy appearance; freely and remontant flowering habit from early spring until the autumn; dark red-colored single flowers; vernalization treatment not required for flowering; and good container and garden performance.

2 Drawing Sheets

1

Botanical designation: *Dianthus hybrida*.

Cultivar denomination: 'KonD1335K1'.

BACKGROUND OF THE INVENTION

The present invention relates to a new and distinct cultivar of *Dianthus* plant, botanically known as *Dianthus hybrida*, grown commercially as a container and garden plant and hereinafter referred to by the name 'KonD1335K1'.

The new *Dianthus* plant is a product of a planned breeding program conducted by the Inventor in Westerbork, The Netherlands. The objective of the breeding program is to create new hardy *Dianthus* plants with remontant flowering habit with good container and garden performance.

The new *Dianthus* plant originated from a cross-pollination in May, 2012 of a proprietary selection of *Dianthus hybrida* identified as code number D11229, not patented, as the female, or seed, parent with a proprietary selection of *Dianthus hybrida* identified as code number D934, not patented, as the male, or pollen, plant. The new *Dianthus* plant was discovered and selected by the Inventor in July, 2013 as a single flowering plant from within the progeny of the stated cross-pollination in a controlled environment in Westerbork, The Netherlands.

Asexual reproduction of the new *Dianthus* plant by vegetative terminal cuttings propagated in a controlled greenhouse environment in Chicago, Ill. since September, 2013 has shown that the unique features of this new *Dianthus* plant are stable and reproduced true to type in successive generations of asexual reproduction.

SUMMARY OF THE INVENTION

Plants of the new *Dianthus* have not been observed under all possible combinations of environmental conditions and cultural practices. The phenotype may vary somewhat with variations in environmental conditions such as temperature and light intensity, without, however, any variance in genotype.

2

The following traits have been repeatedly observed and are determined to be the unique characteristics of 'KonD1335K1'. These characteristics in combination distinguish 'KonD1335K1' as a new and distinct *Dianthus* plant:

1. Uniformly mounding and upright to broadly spreading plant habit; dense and bushy appearance.
2. Freely and remontant flowering habit from early spring until the autumn.
3. Dark red-colored single flowers.
4. No vernalization requirement for flowering.
5. Good container and garden performance.

Plants of the new *Dianthus* differ primarily from plants of the female parent selection in the following characteristics:

1. Plants of the new *Dianthus* are more vigorous than plants of the female parent selection.
2. Plants of the new *Dianthus* have larger flowers than plants of the female parent selection.

Plants of the new *Dianthus* differ primarily from plants of the male parent selection in the following characteristics:

1. Plants of the new *Dianthus* have are not as vigorous as plants of the male parent selection.
2. Plants of the new *Dianthus* and the male parent selection differ in flower form as plants of the new *Dianthus* have single flowers whereas plants of the male parent selection have semi-double flowers.

Plants of the new *Dianthus* can also be compared to plants of *Dianthus caryophyllus* 'Fusilier', not patented. In side-by-side comparisons, plants of the new *Dianthus* differ primarily from plants of 'Fusilier' in the following characteristics:

1. Plants of the new *Dianthus* have shorter flowering stems than plants of 'Fusilier'.
2. Plants of the new *Dianthus* have larger flowers than plants of 'Fusilier'.
3. Plants of the new *Dianthus* have single-type flowers whereas plants of 'Fusilier' have semi-double flowers.

BRIEF DESCRIPTION OF THE PHOTOGRAPHS

The accompanying photographs illustrate the overall appearance of the new *Dianthus* plant showing the colors as

true as it is reasonably possible to obtain in colored reproductions of this type. Colors in the photographs may differ slightly from the color values cited in the detailed botanical description which accurately describe the colors of the new *Dianthus* plant.

The photograph on the first sheet (FIG. 1 of 2) is a side perspective view of a typical flowering plant of 'KonD1335K1' grown in an outdoor nursery.

The photograph on the second sheet (FIG. 2 of 2) is a close-up view of a typical flowering plant of 'KonD1335K1'.¹⁰

DETAILED BOTANICAL DESCRIPTION

Plants used in the aforementioned photographs and following observations and measurements were grown during the summer in ground beds and in 2.5-quart containers in a glass-covered greenhouse in Elburn, Ill. and under cultural practices typical of commercial container *Dianthus* production. During the final production phase of the plants, day temperatures ranged from 13° C. to 27° C., night temperatures ranged from 7° C. to 18° C. and light levels ranged from 5,000 to 8,000 foot-candles. Plants were 18 weeks old when the photographs were taken and 20 weeks old when the description was taken. In the following description, color references are made to The Royal Horticultural Society Colour Chart, 2015 Edition, except where general terms of ordinary dictionary significance are used.

Botanical classification: *Dianthus hybrida* 'KonD1335K1'.³⁰
Parentage:

Female, or seed, parent.—Proprietary selection of *Dianthus hybrida* identified as code number D11229, not patented.

Male, or pollen, parent.—Proprietary selection of *Dianthus hybrida* identified as code number D934, not patented.

Propagation:

Type.—By vegetative terminal cuttings.

Time to initiate roots, summer.—About one week at 40 temperatures ranging from 20° C. to 21° C.

Time to initiate roots, winter.—About two weeks at temperatures about 20° C. to 21° C.

Time to produce a rooted young plant, summer and winter.—About six to seven weeks at temperatures 45 ranging from 7° C. to 16° C.

Root description.—Fine, fibrous; white in color, actual color of the roots dependent on substrate composition, water quality, fertilizer, substrate temperature and age of roots.

Rooting habit.—Freely branching; medium density.

Plant description:

Plant and growth habit.—Herbaceous perennial, typically grown as a container and garden plant; uniformly mounding, upright to broadly spreading plant 55 habit; vigorous growth habit.

Plant height, soil level to top of foliar plane.—About 12 cm.

Plant height, soil level to top of floral plane.—About 16 cm.⁶⁰

Plant diameter or spread.—About 24 cm.

Lateral branches.—Branching habit: Freely basal branching habit with numerous primary lateral stems; each primary lateral stem with secondary lateral stems potentially forming at every node. 65 Length, lateral stems: About 10 cm. Diameter, lateral

stems: Thick, about 2.5 mm. Internode length, proximally: About 4 mm, leaves are densely stacked. Strength: Strong, flexible. Aspect, lateral stems: Mostly outward then curving upright. Cross-section: Round, solid. Texture and luster: Smooth, glabrous, glaucous; matte. Color: Close to 146A; thin waxy cuticle, close to 189A to 189B.

Leaf description:

Arrangement.—Opposite, simple; sessile.

Length.—About 4.5 cm.

Width.—About 3 mm.

Shape.—Lanceolate to acicular.

Apex.—Narrowly acute.

Base.—Attenuate; decurrent.

Margin.—Entire.

Texture and luster, upper and lower surfaces.—

Smooth, glabrous, glaucous; matte.

Venation pattern.—Parallel.

Color.—Developing leaves, upper and lower surfaces:

Close to 146A; thin waxy cuticle, close to 189A to 189B. Fully expanded leaves, upper and lower surfaces: Close to 147A; thin waxy cuticle, close to 189A giving a bluish green appearance to the leaves; venation, close to 147A. Fully expanded leaves, lower surface: Close to N137B; thin waxy cuticle, close to 189A; venation, close to N137B.

Flower description:

Flower form and flowering habit.—Terminal and axillary single flowers arranged singly or in pairs; freely flowering habit with numerous flowers developing during the flowering season; flowers face mostly upright to slightly outwardly.

Natural flowering season.—Consistent remontant flowering habit from the early spring until the autumn in northern Illinois; plants do not require a vernalization treatment to initiate flowering; plants begin flowering about six to eight weeks after planting.

Fragrance.—Faintly fragrant; clove-like, sweet.

Flower buds.—Length: About 1.25 cm. Diameter: About 2.5 mm. Shape: Oblong; styles not extruded. Texture and luster: Smooth, glabrous; matte. Color: Close to 146A.

Flower diameter.—About 2.2 cm.

Flower depth.—About 1.75 cm.

Petals.—Quantity and arrangement: Five petals arranged in a single whorl. Length: About 1.2 cm. Width: About 2 cm; at the base, about 1.1 mm. Shape: Spatulate, fan-shaped. Apex: Praemorse. Base: Elongated, tapering to a point. Margin: Entire. Texture and luster, upper and lower surfaces: Smooth, glabrous; velvety; matte. Color: When opening, upper and lower surfaces: Close to 53C becoming closer to 53A to 53B with development. Fully opened, upper and lower surfaces: Close to 53A to 53B; throat, close to 53A; venation, similar to lamina; color does not change with development.

Sepals.—Quantity and arrangement: Five sepals arranged in a single whorl; proximal 75% portion of the sepals are fused into a tubular-shaped calyx. Length: About 1.6 cm. Sepal width, at base of "free" portion: About 3 mm. Shape: Oblong. Apex: Acute. Margin: Entire. Texture and luster, upper and lower

surfaces: Smooth, glabrous; matte. Color, inner surface: Close to 146B. Color, outer surface: Close to 146A.

Peduncles.—Length: About 2.5 cm. Diameter: About 1 mm. Strength: Strong, flexible and wiry. Aspect: 5 Mostly erect. Texture and luster: Smooth, glabrous; matte. Color: Close to 146A; thin waxy cuticle, close to 189A to 189B.

Pedicels (when flowers arranged in pairs).—Length: About 1.5 cm. Diameter: About 1 mm. Strength: Strong, flexible and wiry. Aspect: About 30° to 45° from the peduncle axis. Texture and luster: Smooth, glabrous; matte. Color: Close to 146A; thin waxy cuticle, close to 189A to 189B.

Reproductive organs.—Stamens: Quantity: About five stamens per flower. Filament length: About 7.5 mm. Filament color: Close to NN155C. Anther length: About 1 mm. Anther shape: Oblong. Anther color: Close to 10D. Pollen: None observed. Pistils: Quantity: About two per flower. Pistil length: About 1.75 15 20

cm. Stigma shape: Pointed, curled. Stigma color: Close to NN155C. Style length: About 1.25 cm. Style color: Close to NN155C. Ovary shape: Oblong. Ovary texture: Smooth, glabrous. Ovary color: Close to 144A. Fruits and seeds: Fruit and seed development have not been observed on plants of the new *Dianthus* to date.

Pathogen & pest resistance: Plants of the new *Dianthus* have not been observed to be tolerate Botrytis (*Botrytis cinerea*) and Cercospora (*Cercospora* spp.). Plants of the new *Dianthus* have not been observed to be resistant to pests and other pathogens common to *Dianthus* plants.

Garden performance: Plants of the new *Dianthus* have been observed to have good garden performance and to tolerate wind, rain and to be suitable for USDA Hardiness Zones 5a to 9a.

It is claimed:

1. A new and distinct *Dianthus* plant named 'KonD1335K1' as illustrated and described.
